(57) **CLAIM**

The ornamental design for an electric guitar body, as shown and described.

DESCRIPTION

FIG. 1 is a top perspective view of an electric guitar body showing the first embodiment of my new design;

FIG. 2 is a top plan view thereof;

FIG. 3 is a right-side elevational view thereof;

FIG. 4 is a left-side elevational view thereof;

FIG. 5 is a bottom plan view thereof;

FIG. 6 is a rear elevational view thereof;

FIG. 7 is a front elevational view thereof.

FIG. 8 is a top perspective view thereof, showing additional components of a guitar illustrated in broken, dashed lines;

FIG. 9 is a top perspective view of an electric guitar body showing the second embodiment of my new design;

FIG. 10 is a top plan view thereof;

FIG. 11 is a right-side elevational view thereof;

FIG. 12 is a left-side elevational view thereof;

FIG. 13 is a bottom plan view thereof;

FIG. 14 is a rear elevational view thereof; and,

FIG. 15 is a front elevational view thereof.

In FIG. 8, the broken lines representing additional components of a guitar form no part of the claimed design.
